UNITED STATES PATENT OFFICE.

CARL C. KING, OF WASHINGTON, DISTRICT OF COLUMBIA.

SAFETY-RAZOR.

1,200,426.

Specification of Letters Patent.

Patented Oct. 3, 1916.

Application filed May 26, 1909. Serial No. 498,490.

To all whom it may concern:

Be it known that I, CARL C. KING, a citizen of the United States, residing at Washington, in the District of Columbia, have invented a new and useful Improvement in Safety-Razors, of which the following is a specification.

This invention relates generally to safety razors, and more particularly to the manner 10 of clamping or holding the blade or blades, the object being to provide a holder in which thick or hollow ground blades or other single edged blades, or a double edged blade, if desired, may be employed.

15 Another object of the invention is to provide the handle of the holder with a swiveled finger rest whereby the manipulation of the device is greatly facilitated.

A further object of the invention is to 20 provide exceedingly quick and simple means for securing the blade or blades whereby a part revolution of a locking cam or of the handle draws together and binds the several members of the razor.

25 With these objects in view, my invention consists in the novel features of construction and combination of parts hereinafter described and pointed out in the claims.

In the drawing forming a part of this 30 specification: Figure 1 is a side view of a safety razor constructed in accordance with my invention. Fig. 2 is a face view, the lower end being shown in section to illustrate the manner of connecting the swiveled 35 finger rest. Fig. 3 is a sectional elevation showing the manner of fastening the blades, said view being taken on the line 3—3 of Fig. 4. Fig. 4 is a longitudinal sectional view of the parts illustrated in Fig. 3. Fig. 40 5 is a detail perspective view of the locking device or cam disk. Fig. 6 is a detail view of the clamping and shaping plate. Fig. 7 is a view showing in partial sectional elevation a slightly modified form of construction.

45 In carrying out my invention I employ a double edged guard A, which is provided with the usual construction of comb edges A', and with openings A² (and a central 50 opening may be provided in certain instances as shown in Fig. 7). At either end of this guard I preferably form a boss B, having a threaded aperture B' in which the threaded end C' of the handle C can be 55 screwed whenever desired. The upper face

of this guard is provided with longitudinal ribs D and at one end stop lugs E are provided to limit the movement of the blades arranged upon the guard and held in place by means of the clamping plate F, said plate F preferably having a central longitudinal rib F' from which extends depending pins F², which are adapted to be passed through the apertures A² in the guard plate, and it will be noted that each of these depending pins is provided with a notch or recess F³. The blades G are formed with longitudinal grooves G', produced adjacent the back or thick edge of the blade, and when placed upon the guard plate the longitudinal ribs of said plates fit into the longitudinal grooves produced in the blades and the clamping plate F is then arranged to cover the said blades G, the pins F² passing downwardly between the opposing backs of 60 said blades and through the guard plate; and for the purpose of securely clamping the plate F to the guard plate and at the same time clamping the blades for operation, I employ a knob or locking cam H 70 which may be pivoted to the guard plate by a short shank H' headed into the central portion of the guard plate in one construction as shown in Fig. 4. This knob or locking cam is constructed with a disk portion 75 H² which is in the form of a double cam or wedge, inasmuch as it gradually increases in thickness as shown at H³ and terminates in a stop H⁴, there being notches H⁵ in order to permit the shaping plate pins to be withdrawn, it being understood, of course, that this knob or locking cam is turned so as to bring the double wedges into engagement with the notched portion of the pins, thereby drawing down the clamping plate firmly 80 upon the blades as clearly shown in the drawings.

In Fig. 7 the clamping plate is provided with a central depending pin (or this central pin may be secured to the guard plate 90 as a matter of choice), whereas in the other constructions said central pin is dispensed with. In this construction the knob or locking cam turns upon a central sleeve.

When single edged blades are employed, they may be slid in from one end of the guard and clamping plates until they are stopped by engaging the stop lugs E at the opposite end, and the clamping operation 100 can then take place.

It is apparent that a double edged flexible blade may be used in the holder; the depending pins acting as positioning means and the wedge-shaped cams of the locking device drawing the cap toward the guard plate when the handle is rotated and flexing the blade transversely over the ribs of the guard plate.

After the parts are clamped the razor can be used with the parts arranged as shown in Figs. 1, 2, 3 and 4, or the threaded end of the handle—where the handle is made detachable from the locking cam—may be introduced into either one of the threaded lugs or bosses at the end of the guard plate, as may best suit the user.

Now, in order to render the device easy of manipulation, I provide a swiveled finger rest I, bifurcated, or of other suitable form, as shown at I', to receive the finger, said finger rest being mounted upon the end I² and secured by means of the screw I³, this construction permitting the free rotation of the rest upon the reduced end of the handle, and it will be found that by having the end of the handle turn freely, the razor can be more freely manipulated than it could be without such freely turning finger rest.

While I have shown the finger rest mounted pivotally upon a reduced end of the handle, it is apparent that other simple means of forming a pivot joint between the body of the handle and the finger rest may be employed, and I do not desire to limit myself to the construction shown.

It will be seen that I provide a safety razor capable of employing either single edged blades or a double edged blade as may be desired, and it will be noted that the said blades or blade can be quickly and most easily attached to or detached from the holder by a part revolution of the locking cam, and it will be still further noted that the handle, owing to the swiveled finger rest, greatly facilitates the manipulation of the device as a shaving instrument.

Having described my invention, what I claim as new and desire to secure by Letters Patent is:

1. In a razor of the kind described, the combination with a guard plate and single edged blades, of a clamping plate having notched depending pins, one of said plates being provided with longitudinal ribs, said ribs bearing upon the single cutting edge blades, a handle, and a locking cam having substantially wedge-shaped disks engaging the notches of the pins and drawing together

and binding the guard plate, blades and clamping plate.

60

2. In a safety razor, the combination with a detachable handle having a threaded end, of a guard plate carrying detachable blades having longitudinal grooves, a blade clamping plate having longitudinal ribs co-acting with the longitudinal grooves of the blades, notched pins carried by the clamping plate, a knob provided with cam-shaped disks engaging the notched depending pins of the clamping plate, said knob having a threaded bore receiving the threaded end of the handle.

3. In a safety razor, a holder comprising a plate having notched depending pins, a plate having openings to receive said pins, a handle, and a rotatable locking cam carried by said handle and having oppositely disposed wedge-like flanges adapted to engage the notches of said pins when the cam is rotated, thereby drawing and clamping the said plates together, stops located on said flanges, and means co-operating with said stops and holding said cam against rotary movement when in locking position.

4. In a safety razor, a holder comprising a guard plate having perforations, a blade clamping plate having notched depending pins, and a rotary locking cam having a circular shaped disk with oppositely disposed semicircular notches along its marginal perimeter with the portions of the perimeter of the disk between the notches formed thin at one end and increasing in thickness wedge-like and terminating at a stop at the other end, the wedge-like portions of the locking cam engaging the notches of the depending pins of the clamping plate to bind the parts together.

5. In a safety razor, a holder comprising a guard plate, a clamping plate, notched pins carried by one of said plates, and a detachable handle provided with means on one end thereof engaging said notched pins when the handle is rotated whereby a part revolution of said handle draws and holds the handle and the said plates together.

6. In a safety razor, the combination with blade holding means provided with shouldered pins, of a detachable handle carrying means engaging the shoulders of the pins thereby attaching said handle to the blade holding means.

CARL C. KING.
